UNITED STATES PATENT OFFICE

2,418,367

CONTAINER AND CLOSURE THEREFOR

Joseph Pulvers, Brooklyn, N. Y.

Application June 9, 1944, Serial No. 539,515

1 Claim. (Cl. 229—5.7)

1

This invention relates to containers, and has for its principal object the provision of an inexpensive container for dry chemicals, foods, and other materials, the container being provided with novel closure means at the upper end thereof which may be applied to the container and removed therefrom with ease and facility, and which will afford a substantially air-tight seal.

Containers of this general character are normally made from fiber board, chip board, and other inexpensive materials, the container having any suitable permanent closure at the lower end. In the event that a metal upper wall is provided on the container and a screw closure formed, difficulty has been experienced in removing the contents, particularly in cases where they have become caked or otherwise adhered together. In instances wherein the entire head is removable, difficulty has been experienced in providing a suitable seal which will prevent the contents from sifting out in the event that the container is placed upon its side. Also, in most cases wherein a full removable head is provided, the closure is damaged during its first removal, and cannot thereafter be replaced, should only a portion of the contents be removed in the first instance.

A container closure constructed in accordance with the present invention provides a highly-effective seal, which, if desired, may be made substantially air-tight. Another object of the invention is to provide a container having a closure head which may be quickly applied and locked in closing relation, thus definitely preventing loss of contents due to accidental opening. The closure may, with equal facility, be removed and the contents taken from the container with ease, whether such contents comprise comminuted material or are in one piece, as in the case of paraffine or other solids.

A further object of the invention is to provide a closure element for a container of the type described, which will strengthen the container and will increase its effective life, permitting continued re-use.

In the drawings:

Fig. 1 is a side elevation, partially in section and partially broken away, of one embodiment of the container and closure therefor forming the present invention, the portion in section being taken on line 1—1 of Fig. 2.

Fig. 2 is a top plan view, partially in section and partially broken away, of the container shown in Fig. 1.

2

Fig. 3 is a broken, vertical section showing a modified form of top closure securing means.

Fig. 4 is a broken vertical section showing another form of top closure means.

5 Fig. 5 is a top plan view, partially in section and partially broken away, of the structure shown in Fig. 4.

Fig. 6 is a broken vertical section showing another form of top closure means, the section being taken on line 6—6 of Fig. 8.

Fig. 7 is a top plan view, partially in section and partially broken away, of the structure shown in Fig. 6.

10 Fig. 8 is a broken side elevation of the structure illustrated in Figs. 6 and 7.

Fig. 9 is a broken vertical section of still another top closure embodying the present invention, the section being taken on line 9—9 of Fig. 10.

15 Fig. 10 is a top plan view of the structure illustrated in Fig. 9.

20 Referring now to the structure illustrated in Figs. 1 and 2, the container is of the general cylindrical type having annular side walls 10 which may be formed of heavy cardboard, fiber board, or any other suitable material, including metal, plastic material, or otherwise. The bottom closure 11 is permanently secured to the container and forms no part of the present invention. At the upper 25 end of the container, a continuous ring 12 of metal, or any other suitable material, is positioned, the upper edge 13 of the ring being planar with the upper edge 14 of the container.

This ring is formed with a plurality of spaced, 30 threaded apertures 16 which are aligned with apertures 17 adjacent to the upper edge 14 of the container. A headed screw 18 passes through each of apertures 17, and into threaded aperture 16 in ring 12. The showing of the thickness of ring 12

35 in Fig. 1 is, of course, exaggerated, although the thickness of this ring is a matter of choice, and in many instances wherein it is desired to provide additional reinforcement for the upper end of the container, a ring formed of heavy gauge

40 metal may be desired. Except for the thickness of this ring, however, the diameter of the upper discharge opening of the container is the same as the diameter of the container. This would be otherwise if the side walls of the container were

45 tapered, which construction is within the scope of the present invention.

The top closure element 21 may be formed of metal, or any other suitable material, and around its marginal edges is formed with an upwardly-

50 disposed flange 22 and a downwardly-extending

55

annular flange 23. A plurality of bayonet slots 24 are formed in flange 23 at points adjacent to screws 18. When it is desired to affix the top closure to the container, the vertical portions of the bayonet slots are aligned with screws 18, the closure moved downwardly until upper flange 22 is in firm engagement with upper edges 13 and 14 of ring and container, respectively, the closure then rotated to a point wherein screws 18 are positioned at the inner end of the horizontal portions of the bayonet slots, and the screws then tightened.

The number of screws is also a matter of choice, and in case it is desired to make the container substantially air-tight, more screws may be provided. Also, to further increase the sealing qualities of the container, any conventional, flat, annular gasket of resilient material may be placed on the upper edge of the container before the closure is moved into place. This particular arrangement is illustrated in Fig. 3, wherein the annular gasket 26 is positioned on the upper edge of the container. In this instance, also, screws 18 carry relatively large, flat washers 27 to further enhance the sealing qualities of the container closure.

In the embodiment of the invention illustrated in Figs. 4 and 5, the container 10 is formed with the same spaced apertures 17 adjacent to its upper marginal edge, and in this instance, the ring 30 may be split, as illustrated at 31 in Fig. 5. The ring is formed with spaced apertures 32 which receive bolts 33, which may, if desired, be welded in apertures, as shown at 34, or they may be otherwise secured. Bolts 33 are threaded, as shown at 35, and nuts 36 firmly secured downwardly-extending flange 23 of top closure 21 to the side walls of the container. Annular flange 23 of closure 21 is also formed with the same bayonet slots 24, and the closure is applied in the manner previously described, and when in place, nuts 36 are tightened.

The modified arrangement illustrated in Figs. 6, 7 and 8 includes the inner ring 40 having the apertures 41 therein, such apertures receiving hollow, bolt-receiving studs 42. In this instance, ring 40 need not be split, and the ring may first be inserted in the upper end of container 10, so that apertures 43 are aligned with apertures 17 in the container. Studs 42 are formed with splines 45 which, when the studs are forced outwardly in apertures 43, cut keyways 46. This force-fit of studs 42 is sufficient to normally retain studs 42 in the ring, and also prevent rotation thereof. The closure member 21 is formed as in the other embodiments of the invention, and flange 23 is secured against the side walls of container 10 by means of bolts 47 which are received in the internally-threaded bore of studs 42.

In the last form of the invention illustrated in Figs. 9 and 10, container 10 is formed with the usual apertures 17. In this instance, however, the continuous or split ring of the other embodiments is eliminated, and the closure disc 50 may be provided with an upwardly-disposed annular bead 51

5 around its marginal edge, such bead terminating in a downwardly-depending annular flange 52. At spaced points adjacent to the periphery of the closure element 50, there are secured, by means of welding or otherwise, a plurality of spaced angle brackets 53 having vertical portions 54, such vertical portions having threaded apertures 55 therein which receive screws 56. In this instance, apertures 57 in flange 52 need not be of the bayonet type, since the closure member 50 is adapted to be initially secured in place before the bolts 56 are screwed into the apertures 55. After the closure is properly positioned, the screws are moved into the apertures, as shown in Fig. 9, and the container is ready for shipment.

20 While four forms or embodiments of the invention have been shown and described herein for illustrative purposes, and the construction and arrangement incidental to several specific applications thereof have been disclosed and discussed in detail, it is to be understood that the invention is limited neither to the mere detail or relative arrangement of parts, nor to its specific embodiments shown herein, but that extensive deviations from the illustrated forms or embodiments of the invention may be made, without departing from the principles thereof.

25 What I claim is:

30 A container and closure therefor, the container being of generally cylindrical shape and having a lower wall, an internal metallic ring positioned at the upper end of the container, the container and the ring having a plurality of spaced, aligned apertures therein, the apertures in the ring being threaded, the closure comprising a metallic member formed with an upwardly-extending annular flange closely fitting the upper, inner marginal edge of the ring, and a downwardly-depending annular flange closely fitting the upper, outer marginal edge of the container, such latter flange having bayonet slots therein aligned with the apertures in the container and ring, and headed screws positioned in such apertures to lock the closure in closing relation after such closure has 35 been rotated to position such screws at the inner ends of the bayonet slots.

40 JOSEPH PULVERS.
